APPARATUS FOR TESTING GEIGER TUBES

Ralph L. De Voll, Grosse Pointe, and John Onia, Berkley, Mich., assignors to Bendix Aviation Corporation, Detroit, Mich., a corporation of Delaware

Application July 27, 1950, Serial No. 176,236

23 Claims. (Cl. 324—24)

1

This invention relates to apparatus for testing Geiger tubes and more particularly to apparatus for determining the response characteristics of Geiger tubes. The invention is especially adapted to provide a permanent record of the response characteristics of a Geiger tube in a minimum period of time without damaging the tube or in any way affecting its future performance.

In general, a Geiger tube has a hollow metallic casing which serves as a cathode and an axially disposed wire which serves as an anode. The tube is filled with a gas which is ionized when a radioactive particle enters the tube. The electrons produced by the gas ionization flow to the anode and the positive ions flow to the cathode forming a current pulse. The number of pulses which are produced when a constant source of radioactivity is at a fixed position from a Geiger tube is dependent upon the voltage between the anode and cathode of the tube.

With relatively low voltages on the tube, small increases in voltage between the anode and cathode produce relatively large increases in the number of pulses from the Geiger tube. When the voltage difference between the anode and cathode reaches an intermediate value, a plateau is reached in which the number of pulses increases only slightly with further voltage increases. At higher voltages, a corona discharge takes place between the cathode and anode, causing the number of pulses through the tube to increase considerably with small increases in voltages. Corona discharges are undesirable since they permanently damage the tube and shorten its life considerably. They also produce an alteration in the response characteristic of the tube.

Since each Geiger tube has a different response characteristic, a permanent record of number of pulses vs. voltage must be obtained for each tube. Heretofore, such records have been obtained by manually varying the voltage between the anode and cathode in predetermined steps. The response of the tube at the predetermined voltages is determined by averaging the measurements obtained from a relatively large number of radioactive emanations. Manual control of the voltage prevents the voltage on the tube from ever rising into the corona discharge region but requires a long time to complete the test, sometimes a matter of hours.

Such attempts as have been made to plot the response characteristics of a tube while automatically varying the voltage on the tube have ended in failure because of the inability to determine

2

the exact voltage at which the corona discharge for each tube will commence. As a result, the voltage on a tube often rises into the corona discharge region before it is cut off.

5 This invention provides apparatus for automatically varying the voltage on a Geiger tube over the safe region of the tube and for cutting off the voltage on the tube before the inception of corona discharge. The invention also provides 10 apparatus for determining the response characteristics of the tube at the different voltage levels and for providing a permanent record of such response characteristic. Thus, the response characteristic of a Geiger tube is automatically determined in a minimum period of time and 15 without any damage to the tube.

An object of this invention is to provide apparatus for determining the response characteristic of a Geiger tube.

20 Another object is to provide apparatus of the above character for obtaining a permanent record of the response characteristic of a Geiger tube.

A further object is to provide apparatus of the 25 above character for determining the response characteristic of a Geiger tube in a minimum period of time.

Still another object is to provide apparatus of the above character for automatically determining the response characteristic of a Geiger tube without damaging the tube or in any way 30 affecting its future performance.

A still further object is to provide apparatus of the above character for gradually varying the 35 voltage on a Geiger tube and providing an indication of the tube response at the different voltage levels.

Another object is to provide apparatus for reducing the cost of Geiger tubes by providing a cheap and reliable test of the tube.

Other objects and advantages will be apparent from a detailed description of the invention and from the appended drawings and claims.

In the drawings:

45 Figure 1 is a schematic diagram of one embodiment of the invention; and

Figure 2 is a curve illustrating a typical response characteristic of a Geiger tube with increases in voltage on the tube.

50 In one embodiment of the invention, a Geiger tube, generally indicated at 10, is provided. The tube has a conductive casing 12, which is filled with a suitable gas such as argon, and a conductive wire 14 axially disposed within the casing in insulated relationship to the casing. The

casing 12 is grounded and the wire 14 is supplied with positive voltage from a movable arm 16 of a potentiometer 18 which is connected across a power supply 20 when a switch 21 is closed.

Amplifier stages 22 are connected to the wire 14, and a multivibrator 24 is in turn connected to the output side of the amplifiers. The output from the multivibrator is connected through a coupling capacitance 26 to the cathode of a diode 28. A resistance 30 is provided between the cathode of the diode 28 and ground. The plate of the diode 28 is connected to the cathode of a diode 32 and to a resistance 34 and capacitance 36 in parallel, one side of the resistance 34 and capacitance 36 being grounded. The plate of the diode 32 is connected through a resistance 38 to a resistance 40 and capacitance 42 in parallel. One side of the resistance 40 and capacitance 42 is grounded.

The grid of a tube 44 is connected to the resistance 38 and is grounded through a resistance 46. The cathode of the tube 44 is connected to the cathode of a tube 48 and to the plate of a tube 50. Positive voltage from a suitable power supply, such as a battery 52, is supplied through a resistance 54 to the plate of the tube 44.

In like manner, the grid of the tube 48 is grounded through a resistance 55 and is supplied with bias voltage by the movable arm 56 of a potentiometer 57, which is connected between the negative terminal and the grounded positive terminal of a suitable power supply, such as a battery 58. Positive voltage is supplied to the plate of the tube 48 through a resistance 59. The resistances 55 and 59 have values corresponding to the resistances 46 and 54, respectively.

The plates of the tubes 44 and 48 are connected to each other through a network which includes resistances 60, 62, 64 and 66 in series. The resistances 60 and 62 are equal to the resistances 66 and 64, respectively. The resistances are supplied at the common terminal between the resistances 62 and 64 with negative voltage from a suitable power supply, such as a battery 67, the positive terminal of which is grounded. The grid of a tube 68 is connected to the common terminal between the resistances 60 and 62 and the grid of a tube 70 to the common terminal between the resistances 64 and 66. The cathodes of the tubes are grounded. The plates of the tubes 68 and 70 are connected to one side of solenoids 72 and 74, respectively. The other side of each solenoid is connected to the positive terminal of the battery 52.

As previously stated, the cathodes of the tubes 44 and 48 are connected to the plate of the tube 50. The grid of the tube 50 is grounded through a resistance 76 and is supplied through a resistance 78 with negative voltage from the battery 67. The cathode of the tube is connected to the battery 67 through a relatively high resistance 80.

The solenoids 72 and 74 act in opposite directions upon a clutch 82 which is provided with a pair of magnetic friction plates 83 and 84 at its extremities. The clutch 82 is mounted on a shaft 85 driven by a motor 86, which is connected to a master switch 87 and a power supply 88. The clutch is positioned by a spring 89 having a disc 90 which is adapted to rotate within a hollow cylinder 91 secured to the center of the friction plate 84. The other end of the spring 89 is suitably secured to a wall 92.

A wheel 96, which may be made from a material such as rubber, is mounted on a shaft 98

between the friction plates 84 and 86. The shaft also carries the movable arm 56 of the potentiometer 57 as well as a pinion gear 100, a clutch plate 102, and a pinion gear 104. The gear 100 has a smaller diameter than the gear 104, which is loosely mounted on a shaft 98 in frictional contact with the clutch plate 102.

The pinion gears 100 and 104 in turn mesh with rack gears 106 and 108, respectively. The rack gear 106 carries at one end a stylus 110 and an outwardly extending arm 112 which may be adjustably positioned on the rack gear. The arm 112 is adapted to engage the movable contact of a normally open switch 114 carried by the rack gear 108. At its other end, the rack gear 106 carries an adjustable arm 116 which is adapted to engage the movable contact of a normally open switch 118, the stationary contact of the switch 118 being grounded. A stop 120 is provided at the same end of the rack gear 108 as the switch 118 to limit the movement of the rack gear.

The stylus 110 contacts a sheet 122 of plotting paper, which is held in fixed position between brackets 124 and 126. The bracket 124 carries a rack gear 128, and a pinion gear 130 driven by a motor 132 meshes with the rack gear. A shaft 134 carries the pinion gear 130, the movable arm 16 of the potentiometer 18 and a hand crank 136. The hand crank 136 is adapted to rotate the shaft 134 in an opposite direction to the rotation provided by the motor 132 so as to return the rack gear 128 to its starting position after the response characteristic of a Geiger tube has been plotted on a sheet 122.

The motor 132 is connected in a series circuit which includes an alternating current power supply 138, a switch 140, the motor 132 and a normally closed switch 142. A switch 144 is provided in parallel with the switch 142 and is adapted to be closed by a finger 145 on the bracket 124 when the brackets 124 and 126 are returned to their zero position by the crank 136. A second finger 146 is also provided on the bracket 124 to open a switch 147 at the zero position of the brackets 124 and 126.

The switch 21 and a switch 148 are ganged to the switch 142 and are operated by a solenoid 150 connected at one end to the positive terminal of the battery 52 and at the other end to the movable contact of the switch 148. The movable contact of the switch 148 is also connected to the stationary contact of the switch 114, and the stationary contact of the switch 148 is connected to the stationary contact of the switch 147, the movable contact of which is grounded.

A neon bulb 154 is connected between the movable contact of the switch 118 and the stationary contact of a switch 156, the grounded movable contact of which is ganged to the switch 140. A capacitance 158 is provided in parallel with the switch 118 and in series with a resistance 160 and the battery 52. In addition to being connected to the neon bulb 154, the stationary contact of the switch 156 is connected to the grid of a tube 162. The grid of the tube 162 is grounded through a resistance 164 and the cathode through a resistance 166. Positive voltage from the battery 52 is supplied to the cathode through a resistance 168 and to the plate through a solenoid 170. The solenoid has an armature 172 with a dog 174 which is adapted to lock the rack gear 108 when the solenoid is energized.

As previously stated, the Geiger tube 18 is filled with gas molecules, such as argon. When a radio-

active emanation penetrates the casing 12, it causes some of the argon molecules to be ionized and electrons and positive ions to be formed. The electrons are attracted to the axial wire 14, which serves as the anode of the Geiger tube, and the positive ions are attracted to the cylinder 12, which serves as the cathode. As the electrons and positive ions move toward the anode and cathode, respectively, they strike other argon molecules and cause some of these molecules to be ionized. The number of argon molecules which are ionized is determined by the force of impact between the molecules and the ions, and this force is in turn dependent upon the voltage between the anode and cathode of the tube.

At low voltages, commonly designated as the threshold region of the Geiger tube response, small changes in voltage produce relatively large changes in the number of molecules which are ionized and which are attracted to the tube electrodes to produce current pulses through the tube. As the voltage increases, a plateau region is reached in which relatively large changes in voltage produce only small changes in the number of pulses. As the voltage on the Geiger tube increases still further, a corona discharge takes place and produces spurious pulses which mask the true number of pulses produced by the radioactive emanations. As previously explained, corona discharges may permanently damage the tube or alter the response characteristics of the tube at the different voltage levels. The threshold, plateau and corona discharge regions of a representative Geiger tube are illustrated by the portions 176, 178 and 180, respectively, of the curve shown in Figure 2.

We have found that the plateau region 178 begins at substantially the same voltage for each tube. We have also found that for most tubes the number of pulses at the end of the plateau region 178 exceeds the number of pulses at the beginning of the plateau region by approximately 20%. By measuring the increase in the number of pulses from the beginning of the plateau region and cutting off the voltage supplied to the tube when the pulse increase is slightly less than 20%, we are able to provide an indication, without damaging the tube, of the response characteristic of the tube over its complete operating range.

We provide an indication of the voltage on the tube at any instant by simultaneously varying the positions of the potentiometer arm 16 and the sheet 122. The positions of the potentiometer arm 16 and the sheet 122 are simultaneously varied when the switch 140 is manually closed, causing the motor 132 to be operated through a circuit which includes the power supply 138, the switch 140, the motor 132 and the normally closed switch 142. As the arm 16 rotates around the potentiometer 18 to increase the voltage on the Geiger tube at a constant rate, the rack gear 128 moves the sheet to the left in Figure 1. Thus, the sheet can be calibrated along a horizontal axis to provide at any instant an indication of the voltage on the Geiger tube.

When a radioactive emanation penetrates the tube, a current pulse having a shape illustrated in curve 182 and an amplitude determined by the voltage on the tube flows through the tube. The pulse is amplified by the amplifier 22 and converted into a rectangular shape by the multivibrator 24, as illustrated in curve 184. Each negative pulse from the multivibrator produces a negative pulse on the cathode of the tube 28

and causes current to flow through the capacitance 36, the diode 28 and the resistance 30. The current charges the capacitance 36, which discharges through the resistance 34 during the intervals between pulses. Because of the large time constant provided by the resistance 34 and the capacitance 36, the capacitance is generally unable to discharge completely during the intervals between pulses, and a voltage proportional to the number of pulses from the Geiger tube 10 builds up across the capacitance 36. The tube 32, resistance 40 and capacitance 42 provide a further smoothing action to the voltage across the capacitance 36.

The voltage across the capacitance 42 biases the grid of the tube 44 and the voltage on the arm 56 of the potentiometer 57 biases the grid of the tube 48. Since the cathodes of the tubes 44 and 48 are connected to the plate of the tube 50, the plate currents through the tubes 44 and 48 flow through the tube 50. The sum of the two plate currents always remains substantially constant since the high value of the cathode resistance 80 prevents the current flowing through the tube 50 from changing materially.

If the bias voltages on the grids of the tubes 44 and 48 are equal, the currents through the tubes are equal, producing similar biases on the grids of the tubes 68 and 70. The equal grid biases on the tubes 68 and 70 in turn cause equal currents to flow through the solenoids 72 and 74. Since the solenoids 72 and 74 act with equal force but in opposite directions on the clutch 82, the clutch is not moved in either direction into engagement with the wheel 96. The gears 100 and 104 therefore remain stationary and the stylus 110 continues to maintain its same vertical position relative to the sheet 122.

If the number of pulses from the Geiger tube 10 increases, the bias on the grid of the tube 44 becomes more negative than the bias on the grid of the tube 48, and the plate currents through the two tubes of each stage become unequal. The unequal plate currents cause the grid bias on the tube 68 to be less negative than the bias on the tube 70 and the current through the solenoid 72 to be greater than the current through the solenoid 74. The solenoid 72 therefore actuates the clutch 82, causing the friction plate 50 to engage the wheel 96. With the motor 86 operating after the closure of the switch 87, the wheel 96 drives the gears 100 and 104 in a direction to move the stylus upwardly in Figure 1 so as to provide an indication of the increased response of the Geiger tube. At the same time, the wheel 96 drives the potentiometer arm 56 in a direction to increase the negative bias on the grid of the tube 48. This causes the bias on the tubes 44 and 48 to become equal at the stylus position corresponding to the number of pulses from the Geiger tube. Similarly, when the number of pulses from the Geiger tube decreases, the stylus moves downwardly and the potentiometer arm 56 moves in a direction to reduce the negative bias on the tube 48.

When the stylus 110 starts to move along the vertical co-ordinate of the sheet 122 from its zero position, the rack gear 106 removes the short circuit across the capacitance 158 by releasing the movable contact of the switch 118. The capacitance 158 is charged by the battery 52 and, after a predetermined delay dependent upon the time constant of the resistance 160 and the capacitance 158, a sufficient voltage is produced across the capacitance to break down the neon

bulb 154. When the tube 154 conducts, it provides a positive bias on the grid of the tube 162 and the resultant current through the tube energizes the solenoid 170. The solenoid attracts the dog 174 towards the rack gear 108, which is then restrained from further movement. The time constant of the capacitance 158 and resistance 160 is chosen so that the rack gear 108 will be locked at a voltage corresponding to the beginning of the plateau region 178 of the Geiger tube response characteristic.

At the time that the rack gear 108 is locked by the dog 174, it has moved through a distance which is approximately 20% greater than the distance advanced by the rack gear 106. As the number of pulses from the Geiger tube increases, the rack gear 106 advances towards the rack gear 108. The rack gear 106 overtakes the rack gear 108 at the end of the plateau region, since the number of pulses is then approximately 20% greater than the number of pulses at the beginning of the plateau region.

When the rack gear 106 overtakes the rack gear 108, the arm 112 on the rack gear closes the switch 114, thereby providing a continuous circuit to the solenoid 150. The solenoid 150 operates to interrupt the supply of voltage to the potentiometer 18 and to the motor 132 by opening the switches 21 and 142, respectively. A holding circuit for the solenoid, including the battery 52, the solenoid 150, the switch 143 and the switch 147, is also provided by the closing of the switch 148. The switch 147 is closed at the instant that the brackets 124 and 126 are moved to the left from their starting position.

The switch 140 is manually opened and the switch 156 manually closed before the rack gear 128 and the brackets 124 and 126 are returned to their starting positions. Opening of the switch 140 prevents the motor 132 from being operated even though the switch 142 may close and closure of the switch 156 causes the dog 174 to be released from the rack gear 108, since current no longer flows through the solenoid 170 and the tube 162. Upon the release of the dog 174, the rack gear 108 is free to move with the rack gear 106 to its starting position. The return movement of the rack gears 106 and 108 takes place because the voltage on the grid of the tube 48 is more negative than the voltage on the grid of the tube 44, causing the solenoid 74 to be energized. The rack gears 106 and 108 move simultaneously to their starting position because of the slippage between the clutch plate 102 and the pinion gear 104.

At the same time that the rack gears 106 and 108 are returning to their zero positions, the brackets 124 and 126 may be returned to their starting position by the manual operation of the hand crank 136. When the brackets 124 and 126 reach their starting position, the finger 146 opens the switch 147, causing the holding circuit through the solenoid 150 to be broken. At the same time, the finger 145 closes the switch 144 and prepares the motor 132 for operation upon the closure of the switch 140. The switch 81 is preferably opened after the stylus 110 reaches its zero position to prevent all possibilities of the motor 86 being operated. The operator then removes the Geiger tube on which the test has been made and the sheet on which the response characteristic has been plotted, and he inserts a new Geiger tube and a fresh sheet of plotting paper before closing the switches 140 and 81.

The apparatus disclosed above has several im-

portant advantages. It obtains and permanently records the response characteristics of a Geiger tube in a minimum period of time. Since it operates automatically, it does not require constant attention, and one semi-skilled operator can simultaneously supervise the testing of several Geiger tubes. The apparatus also reduces to a minimum the number of tubes which are damaged during the testing operation, since the voltage on the tubes very seldom rises into the corona discharge region. As a result of the above advantages, the apparatus may be instrumental in materially reducing the presently high cost of Geiger tubes.

In addition to providing a relatively inexpensive test, the apparatus also provides a reliable and accurate indication of the Geiger tube response characteristic. Because of the continuously variable voltage on the Geiger tube, the number of pulses from the tube is determined for every voltage in the operating region instead of at discrete voltages, the latter being the method used when the response characteristic is obtained manually. Furthermore, by obtaining a continuous recordation of the number of pulses vs. voltage response, a relatively smooth curve is obtained and this curve can be easily interpreted, even by semi-skilled personnel who may have occasion to use the tube.

Although this invention has been disclosed and illustrated with reference to particular applications, the principles involved are susceptible of numerous other applications which will be apparent to persons skilled in the art. The invention is, therefore, to be limited only as indicated by the scope of the appended claims.

What is claimed is:

1. Apparatus for determining the response characteristic of a Geiger tube, including means for applying a continuously variable voltage on the tube, means for providing an indication of the response of the tube to radioactive emanations at the different voltage levels, and means responsive to a predetermined output from the tube to break off the supply of voltage to the tube.

2. Apparatus for determining the response characteristics of a Geiger tube, including means for continuously varying the voltage imposed upon the tube, means for producing electrical pulses upon the penetration of radioactive emanations into the tube, means for determining the number of pulses at the different voltage levels, and means for cutting off the voltage to the tube at a predetermined pulse level.

3. Apparatus for determining the response characteristics of a Geiger tube, including means for continuously varying the voltage on the tube, means for determining the response of the tube to radioactive emanations with different voltages on the tube, means for plotting a curve of the tube response at the different voltage levels to provide a permanent record of the tube characteristic, and means operative at a predetermined level of tube response to cut off the voltage supply to the tube.

4. Apparatus for determining the response characteristics of a Geiger tube, including means for providing the tube with a continuously variable level of energization, means for providing an indication of the number of pulses produced in the tube upon the introduction of radioactive emanations, means for providing an indication of the voltage at which the different pulse levels occur, and means operative to cut off the energy

supply to the tube after the number of pulses has reached a predetermined level.

5. Apparatus for determining the response characteristics of a Geiger tube, including, a first motor, a voltage supply means driven by the first motor for continuously varying the voltage introduced by the voltage supply to the tube, means for determining the response of the tube at the different voltage levels, a second motor, first means driven by the second motor at a relatively high speed for a predetermined period of time, and second means driven by the second motor at a reduced speed in accordance with the determinations of counter response, the second driven means being operative at a predetermined tube response to cut off the first motor and the voltage supply.

6. Apparatus for determining the response characteristics of a Geiger tube, including, a motor, voltage supply means, means driven by the motor to gradually vary the voltage introduced by the supply means to the Geiger tube, means for determining the response characteristics of the Geiger tube at the different voltage levels, a second motor, means operative to activate the second motor in accordance with the determinations of tube response, and means driven by the second motor and operative at a predetermined level of tube response to cut off the voltage supply.

7. Apparatus for determining the response characteristics of a Geiger tube, including, a voltage supply having a variable output voltage, a motor, means driven by the motor for varying the voltage introduced to the Geiger tube, means for determining the response characteristics of the Geiger tube at the different voltage levels, indicating means upon which a permanent record of the response characteristics may be made, means for providing upon the indicating means a recordation of the tube response, means driven by the motor for varying the position of the indicating means in accordance with the rate of change in the voltage introduced to the tube, and means for cutting off the supply of voltage to the tube at a predetermined response level.

8. Apparatus for determining the response characteristics of a Geiger tube, including, a voltage supply having a variable output, means for varying at a predetermined rate the voltage introduced from the voltage supply to the Geiger tube, means for providing an indication of the tube response at the different voltage levels, first means driven at a relatively high speed in accordance with the response of the Geiger tube, means for stopping the first driven means at the beginning of the plateau region of the tube response characteristic, and second means driven at a reduced speed in accordance with the response of the tube and operative upon the first driven means at the end of the plateau region to cut off the supply of voltage to the Geiger tube.

9. Apparatus for determining the response characteristics of a Geiger tube, including, a voltage supply having a variable output, means for varying at a predetermined rate the voltage introduced from the voltage supply to the Geiger tube, means for providing an indication of the tube response at the different voltage levels, means positioned in accordance with the response characteristics of the tube, and means for preparing the positioning means at the beginning of the plateau region of the response characteristics to cut off the voltage supply to the tube at the end of the plateau region.

10. Apparatus for determining the response characteristics of a Geiger tube, including, means for varying the voltage supplied to the tube, indicating means adapted to provide a record of the response characteristics of the tube at the different voltage levels, a motor for simultaneously varying the voltage introduced to the tube and the position of the indicating means, means for recording on the indicating means the counter response at the different voltage levels, and means operative at the end of the plateau region of the response characteristic to cut off the voltage supply and to stop the motor.

11. Apparatus for determining the response characteristics of a Geiger tube, including, a voltage supply having a variable output, means for varying at a predetermined rate the voltage introduced from the voltage supply to the Geiger tube, means for measuring the response of the tube to radioactive emanations at the different voltage levels, a motor, a first rack gear adapted to be driven by the motor at a relatively high speed in accordance with the response of the Geiger tube, means for stopping the first rack gear at a voltage on the Geiger tube corresponding to the beginning of the plateau region of the tube response characteristic, a second rack gear adapted to be driven by the motor at a reduced speed in accordance with the response of the Geiger tube, means carried by the second rack gear for recording the response of the tube to radioactive emanations, and means operative by the second rack gear upon a predetermined movement of the second gear relative to the first gear after the stoppage of the first gear to cut off the supply of voltage to the Geiger tube.

12. Apparatus for determining the response characteristics of a Geiger tube, including, a voltage supply having a variable output, means for varying at a predetermined rate the voltage introduced from the voltage supply to the Geiger tube, means for measuring the response of the tube to radioactive emanations at the different voltage levels, means for providing a recordation of the tube response at the different voltage levels, a motor, a reversible clutch operatively coupled to the motor for movement in a direction to compensate for any difference between the measurement of tube response and the actual value recorded, a first rack gear adapted to be driven by the clutch at a predetermined speed, a second rack gear adapted to be driven by the clutch at a predetermined speed less than that of the first gear to create a differential of movement between the two gears, means for stopping the first gear at a voltage on the Geiger tube corresponding to the beginning of the plateau region of the tube response, and means carried by the second gear for interrupting the supply of voltage to the tube upon a predetermined movement of the second gear towards the first gear after the stoppage of the first gear.

13. Apparatus for determining the response characteristics of a Geiger tube, including, a voltage supply having a variable output, means for varying at a predetermined rate the voltage introduced from the voltage supply to the Geiger tube, means for measuring the response of the tube to radioactive emanations at the different voltage levels, means for providing a recordation of the tube response at the different voltage levels, a motor, and means, including a reversible clutch, operatively coupled to the motor to vary the positioning of the recording means so as to

reduce any difference between the measurement of tube response and the actual value recorded.

14. Apparatus for determining the response characteristics of a Geiger tube, including, a variable voltage supply connected to the Geiger tube, a motor operative to continuously vary the voltage applied by the voltage supply to the Geiger tube, means for measuring the response of the Geiger tube to radioactive emanations at the different voltage levels, a first rack gear adapted to be driven at a predetermined speed in accordance with the response of the Geiger tube to radioactive emanations, a second rack gear adapted to be driven at a predetermined speed less than that of the first gear in accordance with the response of the Geiger tube to radioactive emanations, means connected to the second rack gear to record the movements of the gear, means for stopping the first rack gear at the beginning of the plateau region of the Geiger tube response, means for continuing the movement of the second rack gear until it reaches the first gear at a predetermined position in the plateau region, and means for cutting off the supply of voltage to the Geiger tube when the second gear reaches the first gear.

15. Apparatus for determining the response characteristics of a Geiger tube, including a first motor, means operative by the motor to apply a continuously variable voltage to the Geiger tube, indicating means continuously movable along a first axis in accordance with the change in voltage applied to the Geiger tube, means for measuring the response of the Geiger tube to radioactive emanations which penetrate the tube at the different voltages applied to the tube, a second motor, a clutch adapted to be driven by the motor in one direction for Geiger tube responses of increasing intensity and in the other direction for Geiger tube responses of decreasing intensity, a first rack gear adapted to be driven by the clutch in a direction perpendicular to the first axis, a second rack gear adapted to be driven by the clutch in the same direction as the first rack gear but at a predetermined speed lower than the first gear, means on the second gear for recording the movements of the gear, means for stopping the first gear at a position corresponding to the beginning of the plateau region of Geiger tube response, and means for stopping the second gear and cutting off the supply of voltage to the Geiger tube upon a predetermined movement of the second gear relative to the first gear after the first gear has been stopped.

16. Apparatus for determining the response characteristics of a Geiger tube, including, a first motor, a reversible clutch adapted to be driven by the motor, means for actuating the clutch in accordance with the response of the Geiger tube to radioactive emanations penetrating the tube, a first rack gear adapted to be driven by the clutch, a second rack gear adapted to be driven by the clutch at a predetermined speed less than the first rack gear, means carried by the second rack gear for recording the movement of the gear, indicating means responsive to the movement of the recording means, means operative in accordance with the differential of movement between the first and second rack gears to stop the movement of the gears at a substantially predetermined position in the response characteristics of the Geiger tube, means for varying in a predetermined manner the voltage applied to the Geiger tube, means for varying the position of the indicating means relative to the recording means in accordance with the change in voltage applied

to the Geiger tube and in a direction perpendicular to the direction of movement of the rack gears, and means for cutting off the supply of voltage to the Geiger tube when the tube has reached its predetermined position in the response characteristics.

17. Apparatus for determining the response characteristics of a Geiger tube, including, means for applying a continuously variable voltage to the Geiger tube, means for producing a first control voltage proportionate to the response of the tube, a shaft, means mounted on the shaft for producing a second control voltage variable with the rotation of the shaft, a motor, a reversible clutch adapted to be driven by the motor in a direction determined by the relative values of the first and second control voltages and to drive the shaft in a direction to reduce the disparity between the first and second control voltages, and means positioned in accordance with the movement of the shaft to provide an indication of the response of the tube.

18. Apparatus for determining the response characteristics of a Geiger tube, including, means for applying a continuously variable voltage to the Geiger tube, means for producing a first control voltage proportionate to the response of the Geiger tube to radioactive emanations, means for producing a second control voltage, a pair of solenoids responsive to any differences between the first and second control voltages, a reversible friction clutch operative in accordance with any difference in energization between the two solenoids and in a direction determined by the solenoid having the greater energization, means operative by the clutch to vary the second control voltage in a direction to reduce any difference between the first and second control voltages, and means operative by the clutch to provide an indication of the second control voltage.

19. Apparatus for determining the response characteristics of a Geiger tube, including, means for applying a continuously variable voltage to the Geiger tube, means for producing a first control voltage proportionate to the response of the Geiger tube to radioactive emanations, means for producing a second control voltage, a pair of solenoids responsive to any differences between the first and second control voltages, a reversible friction clutch operative in accordance with any difference in energization between the two solenoids and in a direction determined by the solenoid having the greater energization, means operative by the clutch to vary the second control voltage in a direction to reduce any difference between the first and second control voltages, means operative by the clutch to provide an indication of the second control voltage, and means for cutting off the voltage applied to the Geiger tube after the second control voltage has reached a value corresponding to a predetermined Geiger tube response.

20. Apparatus for determining the response characteristics of a Geiger tube, including, means for applying a continuously variable voltage to the Geiger tube, means for producing a first control voltage proportionate to the response of the Geiger tube to radioactive emanations, means for producing a second control voltage, a first solenoid energized in accordance with the first control voltage, a second solenoid energized in accordance with the second control voltage, a magnetic friction clutch actuated in one direction by the first solenoid and in an opposite direction by the second solenoid, means engaged by the clutch

for movement in one direction when the energization of the first solenoid exceeds the energization of the second solenoid and for movement in an opposite direction when the energization of the second solenoid exceeds the energization of the first solenoid, means operative by the movement of the clutch to vary the second control voltage in a direction to reduce any differences between the first and second control voltages, means for recording the value of the second control voltage with respect to the variable voltage applied to the Geiger tube, and means for cutting off the voltage applied to the Geiger tube after the second control voltage has reached a value corresponding to a predetermined Geiger tube response.

21. Apparatus for determining the response characteristics of a Geiger tube, including, means for applying a continuously variable voltage to the Geiger tube, indicating means, means operative upon the indicating means to provide a record of its position, means for adjusting the position of the indicating means relative to the recording means along a first axis in accordance with changes in the voltage applied to the tube, means for producing a first control voltage proportionate to the response of the Geiger tube to radioactive emanations penetrating the tube, means for producing a second control voltage proportionate to the position of the recording means relative to the indicating means along a second axis substantially perpendicular to the first axis, and means for adjusting the position of the recording means relative to the indicating means along the second axis so as to eliminate any differences between the first and second control voltages.

22. Apparatus for determining the response characteristics of a Geiger tube, including, means for applying a continuously variable voltage to the Geiger tube, indicating means, means operative upon the indicating means to provide a record of its position, means for adjusting the position of the indicating means relative to the recording means along a first axis in accordance with changes in the voltage applied to the tube, means for producing a first control voltage proportionate to the response of the Geiger tube to radioactive emanations penetrating the tube, means for producing a second control voltage proportionate to the position of the recording means relative to the indicating means along a second axis substantially perpendicular to the first axis, a reversible mag-

netic clutch, a pair of solenoids operative in opposite directions upon the clutch in accordance with the values of the first and second control voltages, and means operative by a movement of the clutch to adjust the position of the recording means in a direction along the second axis to reduce any difference between the first and second control voltages.

23. Apparatus for determining the response characteristics of a Geiger tube, including, means for applying a continuously variable voltage to the Geiger tube, indicating means, means operative on the indicating means to provide a record of its position, means for adjusting the position of the indicating means relative to the recording means along a first axis in accordance with changes in the voltage applied to the tube, means for producing a first control voltage proportionate to the response of the Geiger tube to radioactive emanations penetrating the tube, means for producing a second control voltage proportionate to the position of the recording means relative to the indicating means along a second axis substantially perpendicular to the first axis, a reversible magnetic clutch, a pair of solenoids operative in opposite directions upon the clutch in accordance with the values of the first and second control voltages to produce a movement of the clutch dependent upon any unbalance in the control voltages, a first rack gear operative by the clutch for movement along the second axis, a second rack gear operative by the clutch for movement along the second axis at a predetermined speed less than the first gear, means for stopping the first gear upon the application of a predetermined voltage to the Geiger tube, and means for cutting off any voltage to the Geiger tube upon a predetermined movement of the second gear relative to the first gear after the discontinuance of movement of the first gear.
